SASH FASTENER AND HOLDER

Chester O. Goserud, St. Paul, Minn.

Application November 22, 1939, Serial No. 305,671

12 Claims. (Cl. 292—263)

My invention relates to sash fasteners and holders and has for an object to provide a sash fastener and holder by means of which a swinging sash may be easily and readily held in adjusted position with reference to the frame in which the sash is hung.

Another object of the invention resides in providing a sash fastener and holder in which the parts are so constructed as to prevent rattling of the sash.

A still further object of the invention resides in providing a sash fastener and holder which may be readily and easily detached from the bracket, securing the same to the sash without the use of tools or other implements.

An object of the invention resides in providing a sash fastener and holder in which the fastener is positively locked in position with respect to the bracket on the sash regardless of the relative positions of the parts of the sash fastener and the bracket.

A still further object of the invention resides in providing a sash fastener and holder which can be constructed at a nominal expense.

Another object of the invention resides in providing a sash fastener and holder which may be readily removed from the mounting by axial movement with reference thereto.

A still further object of the invention resides in constructing said fastener and holder with a pair of jointed arms having a pintle issuing from one end of one of the arms and adapted to be received within a bearing in the bracket therefor and in further providing a swinging lever pivoted to the arm having the pintle and formed with a finger adapted to overlie a portion of the bracket to hold the arm in position with reference to the bracket.

Another object of the invention resides in constructing the arm with a bead for stiffening the same, and in utilizing said bead for holding the lever in operative position.

An object of the invention resides in constructing the fastener and holder with a friction joint between the arms thereof including a bolt for adjusting the tension between said arms and in providing a locking member for preventing unloosening of the bolt.

A feature of the invention resides in providing a pivot for said lever and in attaching said locking member to the arm carrying the lever through the pivot therefor.

Another object of the invention resides in the specific construction of the parts of the sash

fastener and holder whereby relative rotation of the bolt and nut therefor are prevented.

Other objects of the invention reside in the novel combination and arrangement of parts and in the details of construction hereinafter illustrated and described.

In the drawings:

Fig. 1 is a perspective view of a window illustrating an embodiment of my invention applied thereto.

Fig. 2 is a fragmentary longitudinal sectional view of the window shown in Fig. 1 illustrating the storm sash in open position.

Fig. 3 is a view similar to Fig. 2 showing the storm sash in closed position.

Fig. 4 is a front elevational view of the structure shown in Fig. 3.

Fig. 5 is a view similar to Fig. 3 showing the parts in altered position.

Fig. 6 is a perspective view of the parts of the sash fastener detached from one another.

Fig. 7 is an elevational sectional view of the sash hanger taken on line 7—7 of Fig. 3 and drawn to a greater scale.

Fig. 8 is a cross sectional view taken on line 8—8 of Fig. 3 and drawn to an enlarged scale.

Fig. 9 is a view of a portion of a window and sash similar to that shown in Fig. 2 but taken from the opposite side thereof and illustrating a modification of the invention applied thereto.

Fig. 10 is a view similar to Fig. 4 of the structure shown in Fig. 9.

Fig. 11 is a perspective view similar to Fig. 6 of the parts of the sash hanger shown in Fig. 9.

For the purpose of illustrating the application of my invention, I have shown in Fig. 1 a window, indicated in its entirety by the reference numeral 10. This window comprises a window frame 11 which includes a casing 12 having a header 13 and a sill 14 connected therewith. The frame proper includes vertical frame members 15 which have attached to them stops 16 and 17 to slidably support the usual upper and lower window sash 18 and 19. The sash 18 is formed with stiles 21 and rails 22 connected therewith, while the lower sash 19 is similarly constructed. Both sash include window panes 23 mounted in the stiles and rails of the sash in the usual manner.

In conjunction with the window 10 a storm sash 24 has been illustrated which is constructed with stiles 25, an upper rail 26, a lower rail 27 and an intermediate rail 28. These various rails have mounted in them window panes 29, the same as the sash 18 and 19 of the window proper.

The storm sash 24 is hingedly connected to the frame 11 by means of hinges 31 which are attached to the header 13 of the casing 12 and the upper ends of the stiles 25 and the rail 26 of said sash. The sash may be opened and closed by means of a pull 87 attached to the rail 27.

In conjunction with the storm sash 24 two sash fasteners and holders 32 and 33 are employed which are identical in construction, excepting that one is right handed and the other is left handed. Due to the similarity in construction, only the sash fastener and holder 32 will be described, which has been shown in detail in Figs. 2 to 8 of the drawings.

The sash fastener and holder 32 comprises two jointed arms 34 and 35 which are hingedly connected together by means of a friction joint 36. The arm 34 is hingedly attached to a mounting 37 fast on the stop 17 of window 10, while the arm 35 is detachably secured to a bracket 38 attached to the stile 25 of storm sash 24. These parts will now be described in detail.

The arms 34 and 35 are constructed of sheet material being elongated in form and are rounded at their ends. The arm 34 has a circular hole 39 in one end thereof and another circular hole 41 of larger dimensions in the opposite end. Intermediate the two holes 39 and 41 is formed a rib 42 which is stamped out of the metal from which the arm is constructed and which projects outwardly from the surface of the arm. Arm 35 is similarly constructed with a square hole 43, at one end, whose diagonal dimensions are not greater than the diameter of the hole 41. This arm is constructed at its other end with a pintle 44 rigidly attached thereto which projects outwardly from the arm, as illustrated in Fig. 6. The arm 35 is also constructed with a bead 47 similar to the bead 42 which projects outwardly beyond the surface of the said arm and stiffens and reinforces the same. This bead serves an additional function, which will hereinafter be more fully described.

The joint 36 of the sash fastener and holder includes an elongated locking member 45 which is constructed of sheet material and which is formed at one end with a square hole 46 similar to the hole 43 of arm 35. This locking member has two ears 48 projecting upwardly from the other end thereof. These ears are adapted to be received within two notches 49 in the edges of the arm 35, when the parts are properly assembled and prevent rotation of the member 45 with respect to the arm 35. A lug 51, projecting outwardly from the member 45, engages the arms 35 within the hollow of the bead 47 and holds the member 45 properly spaced relative to arm 35. The joint 36 further includes two fibre or other non-metallic washers 53 and 54 formed with square holes 55 and 56, similar to the holes 43 and 46. A specially constructed bolt 57 is employed having a threaded shank 58 at one end of the same and a head 59 at the other end of the same. Adjacent the head 59 the said bolt is constructed with a circular bearing portion 61 adapted to be received within the hole 41 of arm 34. The said bolt is further constructed with a square portion 62 between the threaded end 58 and the bearing portion 61 which is adapted to be received within the various holes 56, 46 and 55 of the washers 54 and 53 and the locking member 45. When the parts are assembled in the relation shown in Fig. 6 and the bolt 57 placed through the various openings in the parts, and a nut 63 screwed upon the same, friction is pro-

vided between the washer 54 and the surfaces of the member 45 and arm 34, which resists rotation of the two arms and holds the sash fastener in adjusted position. Due to the fact that the member 45 is held from rotation with reference to the arm 35 by means of the ears 48 and the notches 49 in the edges of said arm, both the head and nut of the bolt 51 travel in unison so that unscrewing of the nut by manipulation of the parts of the fastener is prevented.

The mounting 37 is constructed from sheet material and is preferably elongated in form, being provided with an off-set central portion 64 and base portions 65 and 66 connected therewith. A rivet 67 passes through a hole 68 in the off-set portion 64 and through the hole 39 in the arm 34, thus serving to pivotally attach the arm to said mounting. The mounting 37 is further constructed with holes 69 which extend through the base members 65 and 66 and through which screws 71 may pass, which are screwed into the stop 17 to attach the mounting to the frame 11 of window 10.

For the purpose of connecting the sash fastener and holder to the storm sash 24, the bracket 38 is employed. This bracket is constructed from sheet metal which is bent to provide a base 72 and a flange 73 projecting outwardly therefrom. Base 72 is provided with holes 74 through which screws 75 may be driven to attach the said bracket to the stile 25 of sash 24. The flange 73 is provided with a hole 70 at its end, which freely receives the pin 44 on the arm 35 and which serves to pivotally connect said arm to the storm sash 24. Flange 73 is so constructed as to provide a head 76 at the outer portion of the same encircling the hole 70. In detachably securing the sash hanger to the storm sash 24, the said sash is partly opened and the arm 35 sprung sufficiently to the side to permit the end of the pin 44 to ride upon the outer surface of the flange 73 of bracket 38. By shifting the arm about, the pin 44 can be made to enter the hole 70, whereupon the parts are in proper position.

To maintain the parts of the sash fastener and holder in assembled position, a lever 77 is employed which is pivoted intermediate its ends to the arm 35 by means of a rivet 78 extending through said lever and arm and riveted over on the opposite side of said arm, as designated at 79 in Fig. 4. The lever 77 has a pointed finger 81 projecting in the direction of the pin 44 which is off-set from the arm 35 a distance substantially equal to the thickness of the head 76 of bracket 38. When the lever 77 is swung to the position shown in dotted lines at 82 in Fig. 2, the finger 81 is moved away from the pin 44 and the said pin may be applied to the bracket 38 by insertion into the hole 70. When the lever 77 is moved to the position shown in full lines in Fig. 2, the finger 81 overlies the head 76 and restrains relative axial movement between the arm 35 and the bracket 38.

At the end of the lever 77 is provided a finger piece 83 which is bent outwardly therefrom so as to permit of ready manipulation of the lever. Intermediate the finger piece 83 and rivet 78 the lever is bent outwardly, as designated at 84 to clear the bead 47. This provides a ridge 85 substantially at the plane of the surface of the arm 35 on which the lever 77 is mounted. The ridge 85 has a concavity 86 formed therein which is adapted to receive the bead 47. The parts are so constructed that the ridge 85 rides over the bead 47 with considerable resistance and so that, when

the said bead becomes received within the cavity 86 considerable pressure is still exerted by the finger 81 upon the head 76 of bracket 38. Thus the said head is urged against the surface of the arm 35 from which the pin 44 issues and sufficient friction is had between the arm and bracket to prevent rattling of the sash.

Issuing outwardly from the locking member 45 is an elongated lug 88 which is adapted to engage the edge 89 of the arm 34 to restrain swing- 10 ing movement of said arm relative to the arm 35 after the arms are brought into overlying position. A finger piece 91, on the end of the arm 34, becomes spaced from the sash to which the fastener and holder is applied and assists in swinging the 15 fastener and holder in a direction away from the sash. This finger piece is adapted to engage the end of the lug 88 and forms a stop for limiting relative swinging movement of the two arms 34 and 35 to prevent the arms from becoming dead- 20 locked and interfering with the closing of the sash through the pull 87.

The method of use and the operation of the invention are as follows: The fasteners and hold- 25 ers are attached to the stop 17 of the window and to the stiles 25 of the storm sash 24, as shown in Fig. 1, and so that the pivots formed by the rivet 67 and the pin 44 are the same distance from the axes of the hinges 31 of the storm sash. Thus, when the parts are positioned, as 30 shown in Fig. 3, the two arms 34 and 35 of each of the fastener and holders overlie one another. When the sash is open, the parts assume the position shown in Fig. 2. When the sash is drawn closed by means of the pull 87, the parts assume the position shown in Fig. 3. Upon now swinging the two arms 34 and 35 of the sash fastener and holder jointly upwardly through engagement with the finger piece 91 the parts may be brought into the position shown in Fig. 5. In such position the 35 lug 88 restrains relative movement between the arms in a direction tending to open the sash 24 and the sash becomes locked in closing position. When the sash is swung outwardly to its fullest extent, as shown in Fig. 2, finger 91 engages the end of lug 40 88 and prevents further swinging. When the sash is in any of its open positions the arm 34 may be disengaged therefrom by swinging the lever 77 to the position shown in dotted lines at 45 82 in Fig. 2. The pin 44 may then be withdrawn from engagement with the hole 70 of bracket 38 and the storm sash can be removed from the frame.

In Figs. 9 to 11 I have shown a modification of the invention in which another form of locking member for preventing rotation of the nut of the joint bolt with reference to the shank thereof has been illustrated. Inasmuch as the remainder of the invention is the same as that previously described, the description thereof will not be repeated and the same reference numerals preceded by the digit 1 will be used to designate corresponding parts. In this form of the invention an elongated locking member 145 is employed which is constructed with a square hole 146 adapted to fit over the square portion 162 of bolt 151. The said locking member is provided with an off-set 192 intermediate its ends leaving a tongue 193 at the free end of the same. This tongue is constructed with a hole 194 which falls 50 opposite the hole in the arm 135 through which the rivet 178 extends. Rivet 178 also projects through the hole 194 and when riveted over holds the locking member 145 rigidly attached to the arm 135. The manner of installation and the 55

operation of the structures shown in Figs. 9 to 11 inclusive is the same as previously described. This modification has, however, the advantage that the member 145 is positively held in position through rivet 178, whereby strain on the said member is reduced to a minimum.

The advantages of my invention are manifest. An extremely simple and practical construction is provided whereby a storm sash or other pivoted sash may be held in adjusted position. When the arms are swung upwardly the sash is locked in closing position and cannot be opened until the inner sliding sash of the window has been raised. By means of the lever used for holding the arm connected to the sash in engagement with the bracket attached to the sash, disengagement cannot occur unless the said lever is moved to disengaging position regardless of the position of the storm sash with reference to the window. Due to the arrangement of the finger piece for operating the sash with reference to the locking lug, the two arms cannot swing into alignment by merely exerting a pull on the window pull. With my invention the lever is firmly held in position through the bead on the arm and the notch formed on said lever. By means of the construction shown, the locking member for the friction joint bolt serves to engage the edge of the arm movable relative thereto to restrain relative movement between the arms when the arms become disposed in overlying position. The invention is extremely simple to construct and the parts thereof may be easily assembled. By rotating the nut on the end of the joint bolt the friction between the friction washer and the surfaces of the arm and locking member, between which it operates, can be adjusted to meet the requirements. With my invention a lock nut or lock washer for preventing rotation of the nut relative to the bolt is unnecessary, the nut being positively kept in position so as to maintain the desired adjustment.

Changes in the specific form of my invention, as herein disclosed, may be made within the scope of what is claimed without departing from the spirit of my invention.

Having described my invention, what I claim as new and desire to protect by Letters Patent is:

1. A sash fastener comprising a pair of jointed arms, a mounting pivoted to one of said arms, a pintle issuing from the end of the other arm, a bracket having a plate-like head provided with an opening therethrough for the reception of said pintle, said arm having the pintle being adapted to engage said head on one side thereof, a lever pivoted to the arm having the pintle, said lever being provided with a finger adapted to engage the head on the other side thereof, a bead formed on said arm having the pintle and extending longitudinally thereof for reinforcing said arm, and means on said lever for cooperation with said bead to hold the lever in engaging position.

2. A sash fastener comprising a pair of jointed arms, a mounting pivoted to one of said arms, a pintle issuing from the end of the other arm, a bracket having a plate-like head provided with an opening therethrough for the reception of said pintle, said arm having the pintle being adapted to engage said head on one side thereof, a lever pivoted to the arm having the pintle, said lever being provided with a finger adapted to engage the head on the other side thereof, a bead formed on said arm having the pintle and extending longitudinally thereof for reinforcing

said arm, said lever having a notch therein adapted to receive said bead for holding the finger in engagement with said head.

3. A sash fastener comprising a pair of jointed arms, a mounting pivoted to one of said arms, a pintle issuing from the end of the other arm, a bracket having a plate-like head provided with an opening therethrough for the reception of said pintle, said arm having the pintle being adapted to engage said head on one side thereof, a lever pivoted to the arm having the pintle, said lever being provided with a finger adapted to engage the head on the other side thereof, a bead formed on said arm having the pintle and extending longitudinally thereof for reinforcing said arm, said lever having a notch therein adapted to receive said bead for holding the finger in engagement with said head, said lever between the pivot thereof and said notch being raised to clear said bead.

4. A sash fastener comprising a pair of arms adapted to be hingedly connected together at one end of each arm and to be pivotally connected to a sash and window frame at the other ends of said arms, one of said arms having an irregular shaped hole extending therethrough and the other having a cylindrical hole, an elongated holding member disposed between said arms and having an irregular hole opposite that of the first named arm, a bolt extending jointly through said arms and holding member and having an irregular portion of its shank received within the irregular holes of said first named arm and holding member, said second named arm being rotatable relative to said bolt, a nut screwed upon the end of said bolt and clamping said arms and holding member together to provide friction to resist relative swinging of the arms, said holding member extending along the first named arm, and means for attaching the free end of said holding member to said first named arm.

5. A sash fastener comprising a pair of arms adapted to be hingedly connected together at one end of each arm and to be pivotally connected to a sash and window frame at the other ends of said arms, one of said arms having an irregular shaped hole extending therethrough and the other having a cylindrical hole, an elongated holding member disposed between said arms and having an irregular hole opposite that of the first named arm, a bolt extending jointly through said arms and holding member and having an irregular portion of its shank received within the irregular holes of said first named arm and holding member, said second named arm being rotatable relative to said bolt, a nut screwed upon the end of said bolt and clamping said arms and holding member together to provide friction to resist relative swinging of the arms, said holding member extending along the first named arm, means for attaching the free end of said holding member to said first named arm, and a lug formed on said holding member for engagement with a part of the said second named arm to prevent relative rotation in one direction between said arms when the arms are in alignment.

6. A sash fastener comprising a pair of arms adapted to be hingedly connected together at one end of each arm and to be pivotally connected to a sash and window frame at the other ends of said arms, one of said arms having an irregular shaped hole extending therethrough and the other having a cylindrical hole, an elongated holding member disposed between said arms and having an irregular hole opposite that of the first

named arm, a bolt extending jointly through said arms and holding member and having an irregular portion of its shank received within the irregular holes of said first named arm and holding member, said second named arm being rotatable relative to said bolt, a nut screwed upon the end of said bolt and clamping said arms and holding member together to provide friction to resist relative swinging of the arms, said holding member extending along the first named arm, means for attaching the free end of said holding member to said first named arm, a lug formed on said holding member for engagement with a part of said second arm to prevent relative rotation in one direction between said arms when the arms are in alignment, and a finger piece on said second named adapted to engage said lug to limit the swinging movement of said arms in the opposite direction.

20 7. A sash fastener comprising a pair of arms, a mounting pivoted to the end of one of said arms, a pintle issuing from the end of the other arm, a bracket having a head formed with an opening for the reception of said pintle, a lever, a rivet for pivoting said lever relative to said arm having the pintle, said lever being adapted to engage said head for holding the pintle within the opening in said head, said arm having the pintle being constructed at its other end with an irregular shaped hole, an elongated holding member disposed between said arms and having an irregular shaped opening opposite that of the arm having the pintle, said second named arm having at its other end a circular opening, a bolt 25 passing jointly through said arms and holding member and being constructed with an irregular portion of its shank engaging the irregular holes in said holding member and arm having the pintle, said other arm being rotatable on said bolt, a nut screwed on said bolt and clamping said arms and holding member together to provide friction for resisting relative movement of said arms, said holding member extending along the arm having the pintle and being secured at 30 its free end by the rivet forming the pivot for said lever.

8. A sash fastener comprising a pair of arms adapted to be hingedly connected together at one end of each arm and to be pivotally connected to a sash and window frame at the other ends of said arms, one of said arms having an irregular shaped hole extending therethrough and the other having a cylindrical hole, an elongated holding member disposed between said arms and having an irregular hole opposite that of the first named arm, a bolt extending jointly through said arms and holding member and having an irregular portion of its shank received within the irregular holes of said first named arm and holding member, said second named arm being rotatable relative to said bolt, a nut screwed upon the end of said bolt and clamping said arms and holding member together to provide friction to resist relative swinging of the arms, said holding member extending along the first named arm, and ears formed on said holding member and straddling said arm, said ears restraining relative movement between said holding member and first named arm.

9. A sash fastener comprising a pair of arms adapted to be hingedly connected together at one end of each arm and to be pivotally connected to a sash and window frame at the other ends of said arms, one of said arms having an irregular shaped hole extending therethrough and

the other having a cylindrical hole, an elongated holding member disposed between said arms and having an irregular hole opposite that of the first named arm, a bolt extending jointly through said arms and holding member and having an irregular portion of its shank received within the irregular holes of said first named arm and holding member, said second named arm being rotatable relative to said bolt, a nut screwed upon the end of said bolt and clamping said arms and holding member together to provide friction to resist relative swinging of the arms, said holding member extending along the first named arm, ears extending outwardly from said holding member and straddling said first named arm, said first named arm being constructed with notches receiving said ears.

10. A sash fastener comprising a pair of arms adapted to be hingedly connected together at one end of each arm and to be pivotally connected to a sash and window frame at the other ends of said arms, one of said arms having an irregular shaped hole extending therethrough and the other having a cylindrical hole, a holding member disposed between said arms and having an irregular hole corresponding with that of said first named arm, a bolt extending jointly through said arms and holding member and having an irregular portion on its shank received within the irregular holes of said first named arm and holding member, said second named arm being rotatable relative to said bolt, a nut screwed upon the end of said bolt and engaging the first named arm to clamp said arms and holding member together to provide friction to resist relative swinging of the arms and means for restraining relative movement between said holding member and first named arm.

11. A sash fastener comprising a pair of jointed arms, a mounting pivoted to one of the arms, a second mounting for the other arm, a pintle for pivoting said second arm to said second mounting, said arm and second mounting being

separable at said pintle, a lever, a pivot for pivoting said lever to said second named arm at a locality away from said pintle, said lever having a finger adapted to engage a part fixed relative to said second mounting for holding said arm attached to the second mounting, and a portion extending outwardly beyond said pivot at a locality opposite said finger and adapted to overlie said second named arm when the finger is in operative position, said portion of the lever and the arm having juxtaposed parts, a depression formed in said lever and a protuberance formed on said arm and engaging said depression, said finger during swinging of the lever engaging said mounting prior to engagement of the lever with the protuberance, said protuberance when in engagement with the lever forcing the finger into engagement with the mounting to eliminate play therebetween and said depression and protuberance holding said finger in operative position.

12. A sash fastener comprising a pair of jointed arms, a mounting pivoted to one of the arms, a second mounting for the other arm, a pintle for pivoting said second arm to said second mounting, said arm and second mounting being separable at said pintle, a lever, a pivot for pivoting said lever to said second named arm at a locality away from said pintle, said lever having a finger adapted to engage a part fixed relative to said second mounting for holding said arm attached to the second mounting, and a portion extending outwardly beyond said pivot at a locality opposite said finger and adapted to overlie said second named arm when the finger is in operative position, said portion of the lever and the arm having juxtaposed parts, and cam means acting between said parts and serving to move said parts away from one another when the lever is moved into operative position to force said finger into engagement with the mounting to reduce play therebetween.

CHESTER O. GOSEKUD.
